UNITED STATES PATENT OFFICE

160,729

CHILD'S SHOE OR SIMILAR ARTICLE

Francis J. Murphy, Natick, Mass., assignor to Kinderkraft Shoes, Inc., Framingham, Mass.,
a corporation of Massachusetts

Application February 11, 1950, Serial No. 7,895

Term of patent 14 years

(Cl. D7—7)

To all whom it may concern:

Be it known that I, Francis J. Murphy, a citizen of the United States of America, residing in Natick, county of Middlesex, and Commonwealth of Massachusetts, have invented a new, original, and ornamental Design for a Child's Shoe or Similar Article, of which the following is a specification, reference being had to the accompanying drawings, forming a part thereof.

Fig. 1 is a top plan view of a child's shoe, showing my new design;

Fig. 2 is a vertical side view of Fig. 1; and

Fig. 3 is a vertical front elevation of Fig. 1.

I claim:

The ornamental design for a child's shoe or similar article, substantially as shown.

FRANCIS J. MURPHY.
